UNITED STATES PATENT OFFICE.

EDD CARPENTER, OF OWOSSO, MICHIGAN.

HARNESS-PAD PRESS.

SPECIFICATION forming part of Letters Patent No. 271,417, dated January 30, 1883.

Application filed September 23, 1882. (No model.)

To all whom it may concern:

Be it known that I, EDD CARPENTER, a citizen of the United States, and a resident of Owasso, in the county of Shiawassee and State 5 of Michigan, have invented a new and valuable Improvement in Pad-Presses; and I do hereby declare that the following is a full, clear, and exact description of the construction and operation of the same, reference being had to 10 the annexed drawings, making a part of this specification, and to the letters and figures of reference marked thereon.

Figure 1 of the drawings is a representation of this invention in a longitudinal section. 15 Fig. 2 is a perspective section taken through the broken line marked *xx* in Fig. 1. Fig. 3 is a plan view of the clinch-bar. Fig. 4 is a perspective detail, showing the presser-plate. This invention relates to an improved construction of machine for pressing and forming harness-pads, the object being to form and nail up both sides of the pad, and to connect the two without the removal of either side from the block or former; also, to provide devices 25 for pressing the pad and for clinching the nails, which are simple in their construction and capable of being operated with ease and facility. These objects I attain by means of the devices illustrated in the drawings, in 30 which—

A indicates the block or former, provided with straight sides *a* and two concavities or depressions, *B*, separated from each other by a bridge, *C*, arranged transversely in the 35 block between its two straight vertical walls.

D represents a yoke-lever, which embraces the block, and is capable of being shifted along the same, so as to bring it over either one of the recesses *B*. A screw, *E*, which 40 passes through the top of this yoke-lever, is provided with a crank-handle, *e*, whereby the screw can be conveniently turned in order to bring its point into a seat in the curved presser-plate *F*, which latter is employed for 45 pressing the pad-leather into the recess in the block.

G indicates the clinch-bar, which is divided nearly its entire length, and provided at one end with a lever, *H*.

In operating this press the leathers for the two sides *I* of the harness-pad are placed in the two divisions or recesses of the former, and extended over the middle bridge so as to overlap. The clinch-bars *G* are then fitted in the formers, with the leather between the walls of the latter and the clinch-bars, after which the yoke-lever is successively brought over the recesses, and its screw turned down so as to press the presser-plate upon the leather, and thereby force the leather upon the bottom of the recess. By then swinging down the lever greater pressure will be exerted upon the leather, and hence it will be pressed into shape for the pad. The strap *K* is placed upon the clinch-bars, the leather lapped over at its sides upon said strap, and the nails then driven in and caused to clinch upon the strap by coming in contact with the clinch-bars. After this the clinch-bars can be drawn out, and to start the same in such movement their levers 70 can be turned so as to act against the ends of the block.

Having thus described my invention, what I claim is—

In a pad-press for pressing and forming harness-pads, the combination, with the block or former *A*, having the side walls, *a*, and the depressions or concavities *B*, separated by the bridge *C*, of the adjustable yoke-lever *D*, provided with the screw *E*, the curved presser-plate *F*, and the slotted clinch-bars *G*, provided at one end with the spreading-levers *H*, substantially as specified.

In testimony that I claim the above I have hereunto subscribed my name in the presence 85 of two witnesses.

EDD CARPENTER.
